HORSE

Robert A. Lowe, Cleveland Heights, and
Frank F. White, Shaker Heights, Ohio

Application November 1, 1954, Serial No. 32,881

Term of patent 14 years

(Cl. D54—2)

Fig. 1 is a perspective view of a horse, showing our new design;

Fig. 2 is an enlarged cross-section taken along line 2—2 of Fig. 1;

Fig. 3 is a front elevational view of the horse; and

Fig. 4 is an end elevational view of the horse.

We claim:

The ornamental design for a horse, as shown.
